(57) **CLAIM**

The ornamental design for a locker vanity, substantially as shown and described.

DESCRIPTION

FIG. 1 is a perspective view of a locker vanity showing our new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof, the bottom plan view being identical thereto; and,

FIG. 7 is a perspective view thereof with the door in its open position.

1 Claim, 4 Drawing Sheets
